JESSE E. MATEER, OF WILKINSBURG, PENNSYLVANIA, ASSIGNOR TO WESTINGHOUSE ELECTRIC & MANUFACTURING COMPANY, A CORPORATION OF PENNSYLVANIA.

INSULATING-COIL AND METHOD OF MAKING SAME.

1,389,149.

Specification of Letters Patent. Patented Aug. 30, 1921.

Application filed September 1, 1917. Serial No. 189,393.

To all whom it may concern:

Be it known that I, JESSE E. MATEER, a citizen of the United States, and a resident of Wilkinsburg, in the county of Allegheny 5 and State of Pennsylvania, have invented a new and useful Improvement in Insulating Coils and Methods of Making Same, of which the following is a specification.

My invention relates to insulated electrical coils and to methods of economically manufacturing the same, and it has for its object to provide coil coverings having unusually good insulating properties and provided with smooth external surfaces.

15 Heretofore, it has been customary to insulate the individual conductors of a coil by means of tape or paper and to impregnate the entire assemblage of individual conductor coverings, or, in other words, the coil insulation, with bakelite and to subject the coil, in this state, to heat while under pressure. Tape treated with varnish was then wound upon the coil and, when the insulated coil was oversize, it was compressed until it 20 was of the desired dimensions. While the aforementioned construction sometimes gave good service, the insulation frequently separated from the coils on account of being subjected to very high temperatures which softened the varnish or impregnating compound, thereby allowing the insulation to be separated from the coil. When this occurred, which 25 happened frequently in broad coils, it formed spaces between the coil and the separated insulating material, the dead air in which, being a very poor heat conductor, frequently permitted the temperature of the coil to 30 reach a dangerous value.

Another fault of the coil, as formerly insulated, was that the external surface of the coil was rough, which permitted particles of dust to accumulate in the depressions thereof. It is well-known that accumulations of dust interfere with the proper cooling of 45 coils and if, by chance, these accumulations are in the nature of metallic powders or other electrical conducting material, short circuits are liable to develop in the coils.

The object of my invention is to provide 50 insulated coils which may be economically produced and the insulation of which will firmly adhere under all conditions of commercial service. At the same time, I produce

coils which possess smooth external surfaces, thus precluding particles of dust from accumulating thereupon. Also, the external surface of each coil is so treated that it will not tend to adhere to surfaces with which it comes into contact.

Figure 1 of the accompanying drawing is 60 a plan view of a coil constructed in accordance with my invention. Fig. 2 is a sectional perspective view of the coil shown in Fig. 1.

According to my invention, the coil is 65 constructed by winding a plurality of conductors 1, into coil form. The individual conductors are separated from each other by strips 2 of absorptive insulating material, and, in addition, each conductor has an absorptive insulating coating 3, usually the cotton cover customarily applied to conductors.

70 The superposed rows of conductors are insulated from one another by means of an insulating member 4, which extends across substantially the entire width of the coil. When 75 the coil has reached this stage of construction, it is impregnated with a phenolic condensation product, usually bakelite, and is subjected to heat while under mechanical pressure, thereby forming the conductors 80 and the insulating material into a solid mass.

The coil is then wrapped with tape, or some other suitable previous insulating material 85 and is again impregnated with an insulating compound similar to that already used to impregnate the coil and is covered, on each face, with a layer of paper 6, which has been impregnated with a similar compound. The coil is then heated, while under mechanical pressure exerted by shaping 90 plates, and the result is a coil in which the insulating material around and between the individual conductors is integral with the exterior covering of tape and paper and in which the conductors and the insulating material form a solid mass.

95 On account of the insulating material, which serves as a binder, being the same throughout the coil, it will blend and become an integral mass on being heated under mechanical pressure and, being integral, the exterior covering of tape and paper does not leave the conductors. The external layer of paper causes the coil to present a smooth 100 external surface, thus precluding the accumulation of dust thereupon and causing the 105

coil to present a surface that does not tend to adhere to any surface with which it comes in contact.

Another advantage gained by using a phenolic condensation product in place of varnish is that, when drying, the phenolic condensation product tends to shrink the tape which it impregnates, thereby causing the tape to adhere more closely to the coil, while, 10 on the other hand, varnish allows the tape to stretch, causing it to wrinkle and to separate from the coils at some points.

Another advantage of subjecting the coil to the step of heating under mechanical pressure is that is exerted by the means of plates, 15 is that the exterior surface of the coil is smoothed by the application of this mechanical pressure which results in imparting a polished surface to the finished product, 20 thereby insuring that particles of dust will not lodge in the interior irregularities of the coil. This feature has been found to be of great importance for formerly much of the overheating of such coils has resulted from 25 the collection of particles of dust in the many slight irregularities formed on the surfaces of the coils.

While I have shown one form of my invention and described, in detail, one application of the same, it will be obvious to those skilled in the art that it is not so limited but is susceptible of various minor changes and modifications without departing from the spirit thereof, and I desire, therefore, that 35 only such limitations shall be placed thereupon as are imposed by the prior art or are specifically set forth in the appended claims.

I claim as my invention:

1. An insulated coil comprising conductors, strips of pervious insulating material separating the conductors from one another, and layers of pervious insulating material surrounding the entire group of conductors, said layers of insulating material being impregnated with a hardened and a mechanically pressed and smoothed phenolic condensation product to form a permanently smooth exterior surface for said coil.

2. An insulated coil comprising a plurality of conductors each separately wrapped in pervious insulating material and arranged in superimposed rows, insulated spacer strips of pervious material disposed between the rows and the several conductors of the rows, a wrapping of pervious insulating material inclosing the assembled conductors, and a wrapping of paper about the last mentioned wrapping of pervious material, all of the wrappings and spacer strips being impregnated with a hardened and mechanically smoothed phenolic condensation product.

3. The process of insulating coils which consists in separately wrapping conductors with pervious material, interposing strips 65 of pervious material between the several

conductors, wrapping the assembled conductors as a unit with pervious material, impregnating the material with a phenolic condensation product and subjecting the coil thus assembled to the simultaneous action of heat and pressure, wrapping the coil thus treated with additional pervious material and with an outer layer of paper, all impregnated with a phenolic condensation product and subjecting the thus completely assembled coil to further heat and mechanical pressure to further unite all of its component parts.

4. The process of insulating coils which consists in providing an independent insulation for each conductor, interposing insulation between the several conductors, winding insulation about the entire body of conductors, winding paper about the last mentioned insulation, all of the insulation and windings being impregnated with a common binder, and compacting the thus assembled coil and hardening the binder of the insulation and wrapping by the simultaneous application of heat and mechanical pressure.

5. The process of insulating coils which consists in independently wrapping the several conductors constituting the coil, arranging the conductors in superimposed rows, positioning strips of insulating material between the several conductors of each row, positioning a continuous strip of insulating material between the conductors of one row and those of an adjacent row, impregnating the wrapping of the several conductors and the insulating strips with a phenolic condensation product, subjecting the body thus formed to the simultaneous action of heat and pressure, wrapping the body thus treated with further insulating material, including an outer layer of paper, impregnating this material with a phenolic condensation product and subjecting the body thus formed to the simultaneous action of heat and mechanical pressure to intimately unite all of its component parts.

6. The process of insulating coils which consists in separately wrapping conductors with pervious material, interposing strips of pervious material between the several conductors, wrapping the assembled conductors, as a unit, with pervious material, impregnating the material with a phenolic condensation product and subjecting the coil thus assembled to the simultaneous action of heat and pressure, wrapping the coil thus treated with additonal pervious material and with an outer layer of paper, all impregnated with a phenolic condensation product and subjecting the thus completely assembled coil to further heat and pressure to further unite all of its component parts.

7. The process of insulating coils which consists in independently wrapping the several conductors constituting the coil, arranging

ing the conductors in superimposed rows, 5 positioning strips of insulating material between the several conductors of each row, positioning a continuous strip of insulating material between the conductors of one row and those of an adjacent row, impregnating the wrapping of the several conductors and the insulating strips with a phenolic condensation product, subjecting the body thus 10 formed to the simultaneous action of heat and pressure, wrapping the body thus treated with further insulating material, including an outer layer of paper, impregnating this material with a phenolic condensation product and subjecting the body thus formed to the simultaneous action of heat and pressure to intimately unite all of its component parts.

In testimony whereof, I have hereunto 15 subscribed my name this 23rd day of Au- 20 gust, 1917.

JESSE E. MATEER.
